(57) **CLAIM**

The ornamental design for an anti-winkle appliance as shown and described.

DESCRIPTION

The patent or application file contains at least one drawing executed in color. Copies of this patent or patent application publication with color drawing(s) will be provided by the Office upon request and payment of the necessary fee.

2. Anti-winkle appliance

FIG. 2.1 is a back view of an antiwrinkle appliance;
FIG. 2.2 is a back perspective view of an antiwrinkle appliance thereof;

FIG. 2.3 is a side view of an antiwrinkle appliance thereof;
FIG. 2.4 is a side view of an antiwrinkle appliance thereof;

FIG. 2.5 is a left side view of an antiwrinkle appliance thereof;
FIG. 2.6 is a right side view of an antiwrinkle appliance thereof;

FIG. 2.7 is a right perspective view of an antiwrinkle appliance thereof;
FIG. 2.8 is a top perspective view of an antiwrinkle appliance thereof;

FIG. 2.9 is a front perspective view of an antiwrinkle appliance thereof;
FIG. 2.10 is a top front perspective view of an antiwrinkle appliance thereof;

FIG. 2.11 is a bottom front perspective view of an antiwrinkle appliance thereof;
FIG. 2.12 is a front view of an antiwrinkle appliance thereof.

The title of the product incorporating the design is “antiwrinkle appliance”; the product incorporating the design is used as anti-wrinkle appliances; The essential feature of the design lies in the shape of the product incorporating the design.
